US00D578476S

(12) **United States Design Patent**
Takahashi

(10) **Patent No.:** US D578,476 S
(45) **Date of Patent:** ** Oct. 14, 2008

(54) **VACUUM CAPACITOR**

(75) Inventor: **Eiichi Takahashi**, Numazu (JP)

(73) Assignee: **Meidensha Corporation**, Tokyo (JP)

(**) Term: **14 Years**

(21) Appl. No.: **29/300,309**

(22) Filed: **Mar. 11, 2008**

(30) **Foreign Application Priority Data**

Sep. 25, 2007 (JP) 2007-025888

(51) **LOC (8) Cl.** 13-03

(52) **U.S. Cl.** D13/125

(58) **Field of Classification Search** D13/123, D13/125, 133, 154, 184; 361/271, 277, 301.1–301.4, 361/328–330, 763; 438/171, 190, 238, 239, 438/381, 386, 393, 396

See application file for complete search history.

(57) **CLAIM**

The ornamental design for a vacuum capacitor, as shown and described.

DESCRIPTION

FIG. 1 is a front upper perspective view of a vacuum capacitor showing the new design;

FIG. 2 is a front lower perspective view of the vacuum capacitor showing the new design;

FIG. 3 is a front elevation thereof;

FIG. 4 is a rear elevation thereof;

FIG. 5 is a left side elevation thereof, the right side elevation being symmetrical thereto;

FIG. 6 is a top plan view thereof; and,

FIG. 7 is a bottom plan view thereof.
